W. E. BAKER

FLUID FUEL BURNER

Filed March 3, 1924

Inventor.
William E. Baker
By *Washington Atty.*

UNITED STATES PATENT OFFICE.

WILLIAM E. BAKER, OF ERIE, PENNSYLVANIA, ASSIGNOR TO WEBB ENGINEERING COMPANY, OF ERIE, PENNSYLVANIA, A COMMON-LAW TRUST.

FLUID-FUEL BURNER.

Application filed March 3, 1924. Serial No. 696,542.

To all whom it may concern:

Be it known that I, WILLIAM E. BAKER, a citizen of the United States, residing at Erie, in the county of Erie and State of Pennsylvania, have invented certain new and useful Improvements in Fluid-Fuel Burners; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 This invention relates to fluid fuel burning apparatus, and particularly to the construction thereof.

The object of my invention is to provide means whereby the wall of the burner may be protected from excessive heat and thereby will not become warped and distorted.

These and other features of my invention are hereinafter described and pointed out, and are illustrated in the accompanying drawings in which:

Figure 1 is a central longitudinal section of a fluid fuel burner embodying my invention.

Figure 2 is a fragmentary view of the face side of the burner.

Figure 3 is a side elevation of one of the burner nipples of my apparatus.

In these drawings A indicates a plate preferably of sheet metal, which is provided with a plurality of openings *a*, spaced as may be desired to properly distribute the burner tips hereinafter described within the bounds of the face of the burner structure.

40 The rear, or back-side, of the plate A is enclosed by a box-like mixing chamber A' into which air and fluid fuel is supplied by means of the air tube B and fuel pipe B', the said air and fuel being deflected toward the plate A by means of a deflector C.

The side and end plates D and D' extend downward beyond the plate A, as shown at *d* to a point substantially adjacent to the lower ends of the burner nipples E.

50 The burner nipples E are preferably cylindrical in shape, having formed around one end thereof an annular shoulder *e* adapted to seat against the under side of the plate A, and the portion thereof which is

inserted into the openings *a* is then flanged outwardly over the upper side of said plate as shown at *e'*, so that said nipples are firmly secured in said openings *a*.

The opposite, or lower ends of the nipples E are enlarged, internally, to form an internal annular shoulder *e*² therein, against which perforated discs F of lava, or other suitable material are seated, and the edge E' of the nipples E are then flanged inwardly over said discs, thereby firmly securing the discs in place in the nipples E.

The plate A is preferably welded, at its edges, to the sides and ends D and D' of the mixing chamber D, so that the joints are thoroughly sealed.

In order to protect the metal parts of the structure from heat, the space enclosed by the edges *d* and *d'* of the side and end walls of the chamber D, and between the nipples E projecting from the plate A, is filled with asbestos, or other suitable material G, so that the plate A, and walls of the nipples E will not be subjected to the deleterious effects of the fire from the nipples E.

From experience I have found that a burner constructed as herein shown and described will not warp or crack by reason of excessive heat and will at all times be in operative condition.

Having thus fully shown and described my invention so that others can utilize the same, I do not desire to be limited to the exact construction herein described, as many modifications can be made therein without departing from the scope of my invention, therefore what I claim as new and desire to secure by Letters Patent is:

In an apparatus of the class described, a plate having a plurality of openings therethrough, a series of nipples secured in said openings, walls enclosing said plate and forming an enclosed chamber over one side of said plate and forming a flange-like projection around the face of said plate, a series of nipples secured in the openings in said plate, perforated discs of refractory material secured in the opposite end of said nipples, and refractory heat resisting material filling said flange-like projection around said nipples.

In testimony whereof I affix my signature.

WILLIAM E. BAKER.
